UNITED STATES PATENT OFFICE.

HENRY J. GUENTHER, OF NEW YORK, N. Y., ASSIGNOR TO HERMAN LEATHER GOODS CO., INC., OF NEW YORK, N. Y., A CORPORATION OF NEW YORK.

HAND BAG AND THE LIKE.

Application filed January 19, 1926. Serial No. 82,276.

The invention relates to certain improvements in hand bags and similar luggage, provided with a mouth defining frame comprising U-shaped members hinged at their meeting ends and attached to the marginal edges of the bag mouth, said edges being provided with interlocking members adapted to be engaged and disengaged by a slider, these elements constituting means for completely closing the bag mouth when the slider is moved in one direction, and permitting the bag mouth to be fully opened when the slider is moved to its extreme position in the other direction.

15 The invention is illustrated in the accompanying drawings in which:

Fig. 1 is a perspective view of a bag of the club type provided with the closing means, the bag being shown in fully opened position.

Fig. 2 is a perspective view showing the bag closed.

Fig. 3 is a fragmentary perspective view showing the bag partly open with the slider 25 in one extreme position.

Fig. 4 is a fragmentary elevation of the opposite end of the bag with the slider approaching its opposite extreme position.

Referring to the drawings, 1 indicates the 30 body of the bag made of leather or suitable fabric, provided with the usual handles attached to the sides, the mouth of the bag in open position being substantially rectangular and being defined by a metal frame secured to the edges of the mouth and comprising U-shaped sections 2—2 connected at their free ends by pivots 3—3 so that, when the bag is closed, the frame sections come together as indicated in Figs. 2 and 4.

40 It has been customary to lock or fasten the mouths of such bags by various mechanical devices, such as locks, latches, hooks and the like attached to the members of the frame, and the object of the present invention is to dispense with these more or less expensive and complicated fastening means and to employ in lieu thereof a fastening device that will lock the mouth of the bag throughout the extent of the edges of the mouth, which 45 device may be quickly and readily operated to lock and unlock the bag by means of a slider engaging spaced interlocking mem-

bers secured to the edges of the mouth of the bag.

Secured to the edges of the mouth by 55 stitching or other suitable means, and substantially co-extensive with the members 2—2 of the frame, are two stringers 4—4 of tape-like fabric, to which are attached a series of hook-like members 5—5, arranged in 60 staggered relation on the opposite stringers and adapted to be mutually engaged and disengaged by means of a slider 6. One end of each of the stringers 4—4 with its associated interlocking members terminates 65 adjacent one of the frame pivots 3 and is provided with the usual stop 5 which limits the movement of the slider in the closing operation of the latter. The opposite ends of the stringers are extended freely beyond the 70 opposite pivot 3 of the bag frame and are connected together at the extremities of the free extensions by means of a tab 8 which, if desired, may take the form of a card holding device. As indicated in Figs. 1, 2 75 and 3, the free extensions of the stringers are indicated at 7—7 so that, when the bag is closed, said extensions and the means connecting the extremities thereof depend below the hinge or pivot of the bag frame. 80 The object of the free extensions 7—7 are to enable the slider to be moved in the opening operation out of engagement with the interlocking members 5—5 which are closely connected with the edges of the bag mouth adjacent the frame members, and occupy the free extensions of the stringers, thereby permitting the frame and the bag mouth to be 85 opened fully as illustrated in Fig. 1.

What I claim is:

1. A bag comprising a body portion, and a mouth defining frame including two substantially U-shaped sections pivoted together at their meeting ends, a fastener comprising stringers carrying interlocking members and a slider adapted to cause the members to engage and disengage, said stringers being connected to the edges of the bag mouth and terminating at one end adjacent one pivot of the frame, the opposite ends of the stringers extending freely beyond the adjacent frame pivot to form free terminals, and means connecting the extremities of said terminals together. 90 100

2. A bag having a rectangular mouth defining frame pivoted at opposite sides, and fastening means comprising stringers connected to the edges of the bag mouth in alignment with the members of the frame, one end of each stringer extending freely beyond the pivot at one side of the frame,

said free ends being connected at their extremities, interlocking members carried by said stringers, and a slider engaging said stringers to lock and unlock said members. 10

In testimony whereof I affix my signature.

HENRY J. GUENTHER.
